UNITED STATES PATENT OFFICE.

CYRUS MANTZ, OF WASHINGTON, DISTRICT OF COLUMBIA.

NOVELTY CONFECTION BOX.

Application filed May 24, 1924. Serial No. 715,635.

This invention relates to novelty confection boxes and aims generally to improve boxes of this kind in a manner set forth in the following specification.

Referring to the drawings, wherein is shown a single embodiment of my invention selected merely for illustrative purposes;

Figure 1 is a side elevation of my improved box serving as a base for a novelty fixture such as a miniature tree;

Fig. 2 is a plan view partly in section of my improved box;

Fig. 3 is a vertical sectional view taken on the line 3—3 of Fig. 2; and

Fig. 4 is an enlarged fragmentary sectional view similar to Fig. 3, showing the center opening closed by a cap or button.

Referring more particularly to the drawings, I have shown my box as formed of a top 1, base 2 and a plurality of division partitions or plates 3 rigidly secured together. Preferably the box is of cylindrical form and the partitions 3 extend radially from near the center thereof to provide an annular series of segmented chambers to receive drawers, but the particular shape of the box is not essential, as other shapes, such as polygonal boxes, may be used with equal facility. The inner ends of the partitions 3 terminate short of the center of the box, and, in the embodiment shown, are formed with, or are rigidly connected with, a vertical tube 4 to provide a central well opening through the top 1 but closed by the bottom 2. A suitable closure such as the button or cap 5, is preferably provided to close the upper end of the tube 4.

The improved box is provided with drawer section 6, which may be of segmental form and arranged in an annular series between the top 1 and bottom 2, each drawer being held in place by frictional engagement of the sides thereof with the partitions 3. The drawers 6 may be removed edgewise in a radial direction from the chambers formed by the top 1, base 2, and partitions 3. For convenience in removing the drawers from the box, I have provided each of the drawers with a handle 7.

My improved box is adapted to be used as a base in combination with a small decorative device, for example, a miniature tree, electric candle, figure of Santa Claus or other novelty fixture of ornamental design.

For this purpose I provide in the lower part of the well formed by the tube 4, a

resilient holder 9 adapted to surround and support the stem of any desired novelty fixture, that illustrated being a miniature tree. One or more of the drawers 6 and tube 4 may be formed with apertures 10 and 11 respectively (see Fig. 3) to accommodate an electric wire 12 connecting a suitable battery 12^a (shown in dotted lines Fig. 2) with a series of electric lights 13 on the tree 8.

When the fixture is not used in combination with the box, the upper end of the well formed by the tube 4 may be closed by the cap or closure 5 or other means advantageously held fixedly in position by engagement with the resilient holder 9.

Preferably my improved box is covered with an ornamental paper or fabric 14 (see Fig. 4), such as silk or satin, although it is to be understood that such covering may be supplied or omitted to meet the demands of the trade.

Obviously, my invention is not confined to the details shown and described.

What I claim and desire to secure by Letters Patent is:

1. A combination container and decorative fixture comprising a box having top and base portions and radial partitions rigidly connected together, constituting a pedestal, said partitions terminating short of the center of the box thereby to provide a deep central well coextensive in height with said box, a plurality of radial drawer sections arranged within said box and having their ends contiguous to the edges of the top and base portions, said ends constituting the sides of the box, the top of the box being formed with an opening to provide access to said central well and adapted to be closed by a closure cap or the stem of a decorative fixture.

2. A box having top and base portions and radial partitions rigidly connected together, a plurality of drawer sections arranged within said box and bodily removable therefrom, said drawers being adapted in height and width to fit between said radial partitions and to form a substantially continuous peripheral wall for said box coextensive in height with the sides thereof, the top portion of said box being provided with an opening to provide a deep central well closed by the base portion and adapted to receive a closure cap or the stem of a decorative fixture.

3. A combination container and decora-

tive fixture comprising a box having top and base portions and radial partitions rigidly connected together, constituting a pedestal, said partitions terminating short of the center, a vertical tube providing a deep central well connected to the inner ends of said partitions, and a plurality of drawer sections arranged within said box and having their outer ends contiguous to the edges

of the top and base portions to constitute 10 the side walls thereof, the top portion of said box being formed with an opening to provide access to said central well and adapted to be closed by a closure cap or the stem of a decorative fixture.

15

In testimony whereof, I have signed my name to this specification.

CYRUS MANTZ.
